In Great Britain March 14, 1946

Term of patent 3½ years

(Cl. D14—14)

To all whom it may concern:

Be it known that I, Herbert Richard Shaw, a subject of the King of Great Britain, residing at 125 Bill's Lane, Shirley, in the county of Warwick, England, have invented a new, original, and ornamental Design for a Child's Push-Chair, of which the following is a specification, reference being had to the accompanying drawings, forming part thereof.

I claim:

The ornamental design for a child's push-chair, as shown.

HERBERT RICHARD SHAW.
